BURNHAM C. STICKNEY, OF ELIZABETH, NEW JERSEY, ASSIGNOR TO UNDERWOOD
TYPEWRITER COMPANY, OF NEW YORK, N. Y., A CORPORATION OF DELAWARE.

TYPE-WRITING MACHINE.

1,183,825.

Specification of Letters Patent. Patented May 16, 1916.

Application filed December 4, 1911. Serial No. 663,884.

To all whom it may concern:

Be it known that I, BURNHAM C. STICKNEY, a citizen of the United States, residing in Elizabeth, in the county of Union and State of New Jersey, have invented certain new and useful Improvements in Type-Writing Machines, of which the following is a specification.

This invention relates to means for releasing the platens from the line-space wheels of typewriting machines.

One object of the invention is to provide a positively acting train of connections between the line-space wheel and the platen, so that the platen will not either overthrow or overthrow when the usual line-spacing lever is violently actuated, and so as to render the machine more reliable under all conditions; while permitting easy release of the platen from the line-space wheel when desired.

Other objects are to secure these results by inexpensive, compact and durable mechanism, and to construct a device which can be readily applied to existing machines.

The accompanying drawings show the preferred form of my present improvements. In this form, an internal gear device is secured to the line-space wheel. A pinion meshes with said internal gear, and is pivoted to an arm which is fixed to the axle to which the platen is also fixed or connected. I also provide two loose arms, each carrying a pinion to mesh with said internal gear, and each movable independently of the other (and independently of said fixed arm) about the platen axle; such movement of the loose arms being independent also of the line-space wheel. These pinions upon the loose arms are held by a spring in mesh with the gear on the fixed arm. One of the loose arms is disposed on one side of the fixed arm, and the other arm is disposed on the other side thereof. Hence one of the loose arm pinions, by reason of its engagement on the internal gear and with the fixed arm pinion, prevents relative movement or shake of the line-space wheel and platen in one direction, while the other of said loose arm pinions prevents such relative movement or shake in the opposite direction.

It will be understood that one loose arm and its pinion may coöperate with the fixed arm and its pinion and with the internal gear, to lock the platen and line-space wheel

firmly against relative rotation in either forward or backward direction. However, since the pinions may not in all cases mesh perfectly, so as to provide the desired rigid connection between the line space wheel and platen, I contrive that each pinion shall be relied upon only to prevent relative movement in one direction while the other loose pinion is relied upon to prevent such relative movement in the opposite direction.

As a further provision against shaking or relative slipping movement between the platen and the line space wheel, when there is failure on the part of either or both loose pinions to mesh with the teeth on the fixed arm pinion, that is, when the teeth of the pinions interfere instead of interengaging, I provide two auxiliary or reserve loose arms, each carrying a pinion in mesh with said internal gear, for engagement with the said fixed arm pinion. These reserve or auxiliary pinions however are differential from the first-mentioned loose pinions, being preferably of different diameters, so that their teeth are presented to the fixed arm pinion (or common pinion) differently from the first-mentioned loose pinions, so that in case the teeth on either of the first-mentioned loose pinions interfere with the teeth of the common pinion, then the teeth on the corresponding loose pinion are sure to mesh with the teeth on the common pinion, so that play or shake between the line space wheel and platen, in either direction, is entirely avoided. In other words, if one loose arm fails to connect, the other loose arm on the same side of the common pinion must necessarily make the desired connection between the platen and the line-space wheel.

A finger-piece is connected to means for separating the loose pinions from the common pinion concomitantly, so that the platen may be rotated independently of the line space wheel; and springs thereafter return the loose pinions into engagement with the common pinion, thus reconnecting the platen to the line space wheel.

In the present form of the invention, the returning springs operate cams which cam the loose arms to carry their pinions into mesh with the main pinion; the cams being so constructed as to avoid liability of springing of the parts, or separation of the pinions; the cams preferably forming locks which rigidly hold the pinions in mesh.

Other objects and advantages will herein-after appear.

In the accompanying drawings, Figure 1 is a sectional front elevation of the line-spacing platen releasing mechanism. Fig. 2 is a sectional end elevation. Fig. 3 is a sectional plan illustrating the train of gear and pinions. Fig. 4 is a part sectional elevation, showing the platen-releasing movement of the release key; the key being detained in its effective position. Fig. 5 is an enlarged diagram, showing an end elevation of the trains of gears and means for controlling the same. Fig. 6 is a perspective view of a head intended to be fixed to the platen axle and to carry a common pinion and certain of the releasing devices. Figs. 7 to 10 are details of levers or arms loosely mounted upon the platen axle to carry various pinions.

The usual cylindrical platen 1 is fixed by a pin 2 upon an axle 3, which is journaled in the usual manner in the ends of a platen frame, and projects beyond said ends, and carries at each end a knob 5 fixed to the platen axle. Loose upon the platen axle is a line-space wheel 6, having a hub 7. The line-space wheel is held in normal position by a detent 8, and is operated by the usual mechanism, including a driving pawl 9. Fixed upon the line-space wheel 6 is an annular internal gear or rack 10, such as is commonly termed a ring-gear, seated in and fixed to an annular flange 11 which projects from the face of the line-space wheel. Fixed to the platen axle 3 by means of a pin 12 or otherwise, is a hub 12^a of an arm 13, to the free end of which is pivoted a pinion 14 meshing closely with the gear 10. Loose upon the platen axle 3, and preferably journaled to rotate on said hub 12^a, is an arm 15 carrying a pinion 16, also in mesh with the gear 10. Also loosely journaled upon said hub 12^a, is an arm 17 carrying a pinion 18 likewise in mesh with said gear 10, and on the opposite side of 14 from 16.

By means of devices now to be described, the pinions 16 and 18 are brought into mesh with the common pinion 14; pinion 16 then preventing rotation of 14 in one direction, while the pinion 18 prevents rotation of 14 in the opposite direction. This control of pinions 16 and 18 is effected by springs 19 and 20. 19 is attached at one end to a pin 21 on an arm 22 of a bell crank, said arm attached to a rock shaft 23, which carries at its inner end the other arm 24 of the bell crank. This arm 24 has a cam slot 25 to engage a pin 26 which projects from an arm 27, which branches from the arm 15. The spring 19 is pulled downwardly at Fig. 5, swings the arm 24 to the left, and by means of the cam slot 25, urges the arms 27, 15 toward the left together with the pinion 16, the latter rotat-

ing until it strikes a tooth of the pinion 14, in which position the arm 15 and pinion 16 are locked, by reason of the engagement of the locking cam 25 with the pin 26, so that accidental relative movement between the arms 13 and 15 cannot occur, and the pinions remain fixed in their relative positions. The arm 17 carrying pinion 18 is likewise connected; the draw spring 20 engaging a pin 28 on an arm 29 which extends from the rock shaft 30; the latter also carrying at its inner end an arm 31 having a cam slot 32 to engage a pin 33 on a branch 34 of arm 17; the operation of the spring 20 being to carry the arm 17 and the pinion 18 to the right until 18 engages 14, and to lock the parts in this position.

The rock shafts 23 and 30 are mounted in bosses 35 and 36, projecting to the left at Fig. 1 from a plate 37, which is integral with the arm 13 and hub 12^a; said bosses and plate being under or below the axle 3 at Fig. 5 for the sake of compactness, the space above said axle being occupied by the gear trains.

It will be understood that under most circumstances, the loose pinions 16 and 18 will be drawn by the springs 19 and 20 into proper engagement with the common pinion 14 but it is possible that either of the loose pinions may be occasionally presented to the common pinion in such a manner that the tips of the pinion teeth will interfere, so that a complete proper connection will not be made between the line space wheel and platen, to prevent relative slip thereof in either direction. If the teeth of the gear 10 and the pinions are made very fine, however, the possible slip between the line space wheel and platen will be very slight, and where extreme accuracy of adjustment of the platen is not desired, such slight slip may not prove a serious objection; and in such a case only the two loose pinions 16 and 18 may be employed. In the preferred form

of the invention however, the gear and pinion teeth are of substantial size, in order to secure a strong connection between the platen and line space wheel, and hence there is some liability of interference of the pinion teeth. To provide for this contingency I have added an arm 38 similar to 15, and behind the same or to the right thereof at Fig. 1; and I have also provided an arm 39 similar to 17 and behind the latter at Fig. 5.

These arms 38 and 39 are both loose upon the hub 12^a, and are each movable independently of the other and of the remaining arms; and they carry respectively pinions 40 and 41. These pinions are spring pressed or cammed toward the common pinion 14, and they are preferably of substantially larger diameter than the pinions 16 and 18, so as to be substantially differentiated therefrom, whereby when the teeth on 16, for

instance, interfere with the teeth on 14, then the teeth on 40 will mesh with the teeth on 14 to the desired extent for the purpose specified; and conversely if the teeth on 5 40 interfere with or abut against the tips on 14, then the teeth on 16 will properly mesh or engage with the teeth 14; these pinions 16 and 40 being independently movable with relation to 14, and the springs 10 urging or camming constantly both pinions 16 and 33 into mesh with 14. The same holds true of pinions 18 and 41 with respect to 14. Therefore either 16 or 40 is sure to cause a positive connection to be effected in 15 one direction between the line space wheel and platen, and at the same time either 18 or 41 forms a similar connection in the other direction between the line space wheel and platen. In other words the teeth of 16 and 20 40 cannot concomitantly interfere with or become fouled upon the teeth of 14; and the same is true of 18 and 41. Each of the loose pinions 16, 18, 40 and 41 constitutes a lock or locking element, as it locks the platen 25 and line-space wheel together when brought into contact with the pinion 14.

It will be noticed that the spring 19 performs the same function for pinion 41 that it does for pinion 16; said spring being connected at its lower end at Fig. 5 to an arm 42 on a shaft 43 journaled in boss 35; said shaft carrying at its inner end an arm 44 having a cam slot 45 to engage a pin 46 on arm 47, which is rigid with the arm 39; the slot 45, like the remaining slots, being inclined at such an angle as to lock the arm 39 to the arm 13, and the pinion 41 to the pinion 14.

The spring 20 is also connected to an arm 48 fixed to a rock shaft 49 journaled in boss 36, and having an arm 50 provided with a locking cam slot 51, engaging a pin 52 on arm 53, which is rigid with arm 38 carrying pinion 40, so that the latter is also locked in mesh with pinion 14.

When the loose arms 15, 17, 38 and 39 are swung to the positions seen at Fig. 2, the pinion 14 on the middle arm 13 will be disengaged from the pinions on said loose arms, and hence the platen may be rotated independently of the line-space wheel.

The movements of the loose arms from locked position to the disengaged position at Fig. 2, is effected by a finger piece or push button 54 mounted on a pair of stems 55 which pass through the hand wheel 5, and at their inner ends are fixed in a cone-shaped releasing cam 56 mounted to slide along the platen axle 3. This cam engages the inner ends of all the arms 22, 29, 42 and 48, and swings them outwardly into positions seen at Fig. 2, distending the springs 19, 20, and causing the arms 24, 31, 44 and 50 to swing the pinion carrying devices to the released positions at Fig. 2.

The return of the finger piece may be effected by a spring 57 seated in a bore or socket 58 formed in the end of the platen axle 3, and pressing outwardly a pin 59 also fitting in said bore, and at its outward end 70 engaging the button 54; and upon this return movement, the springs 19 and 20 will each rotate its connected pinion-carrying arms as far as possible, and lock them in such positions. 75

The releasing cam 56 may have at its outer end a peripheral groove 60 to receive the ends of the releasing arms 22, 29, 42 and 48, to detain the pinions mechanically in released positions at Fig. 2. 80

Having thus described my invention, I claim:

1. The combination with a platen and a line-space wheel, of a releasable clutching mechanism to connect them, including a finger-piece to release the clutch, four independent arms or bell-cranks movable by said finger-piece, cams independently operable by each of said arms or bell-cranks, and a gear train whose members are locked together by said cams. 85

2. The combination with a platen and a line-space wheel, of a releasable clutching mechanism to connect them, including a finger-piece to release the clutch, four independent arms or bell-cranks movable by said finger-piece, cams independently operable by each of said arms or bell-cranks, and a gear train whose members are locked together by said cams, means being provided 95 for mechanically holding said cams in clutch-releasing positions. 100

3. The combination with a platen and a line-space wheel, of a releasable clutching mechanism to connect them, including a finger-piece to release the clutch, four independent arms or bell-cranks movable by said finger-piece, cams independently operable by each of said arms or bell-cranks, and a gear train whose members are locked together by said cams, means being provided 105 for mechanically holding said cams in clutch-releasing positions; said finger-piece being connected to a conical cam to slide along the platen axle and said arms or bell-cranks being journaled on a device which is fixed to the platen axle and carries one member of the gear train. 110

4. The combination with a platen and a line-space wheel, of a reasonable clutching mechanism to connect them, including a finger-piece to release the clutch, four independent arms or bell-cranks movable by said finger-piece, cams independently operable by each of said arms or bell-cranks, a gear train 120 whose members are locked together by said cams, means being provided for mechanically holding said cams in clutch-releasing positions; said finger-piece being connected to a conical cam to slide along the platen 125 axle. 130

axle and said arms or bell-cranks being journaled on a device which is fixed to the platen axle and carries one member of the gear train, and springs operating on said 5 cam arms to close said clutch.

5. The combination with a platen and a line-space wheel, of a train of gears connecting said platen and line-space wheel, a gear movable into and out of position to lock said 10 train, and positive means to hold the said gear in locking position.

6. In a typewriting machine, the combination of a platen, a line-space wheel, a train of gears connecting said parts, a locking element movable into and out of locking 15 engagement with said train, and means to lock said element in locking position.

7. The combination with a platen and a line-space wheel, of a train of gears connecting said platen and line-space wheel, a locking gear permanently in mesh with a gear of said train and movable into engagement with a second gear to lock the train, and means to positively hold said locking 25 gear in locking position.

8. The combination with a platen and a line-space wheel, of a train of gears connecting said platen and line-space wheel, a locking gear permanently in mesh with a gear of said train and movable into engagement with a second gear to lock the train, a positive lock for the locking gear, and means coöoperating with said lock to positively release the locking gear.

35. 9. The combination with a platen and a line-space wheel, of inter-meshing gears carried by said platen and line-space wheel, a locking gear, resilient means to move the locking gear into position to lock said first named gears, and means to positively lock said locking gear in said position.

10. The combination with a platen and a line-space wheel, of a train of gears connecting said platen and line-space wheel, a locking device, a cam to hold said locking 45 device in locking position, and manual means to positively operate the cam to release the locking device.

11. The combination with a platen and a line-space wheel, of a train of gears connecting said platen and line-space wheel, a lock for said train, and a cam operable to positively hold said lock in locking position.

55. 12. The combination with a platen and a line-space wheel, of inter-meshing gears carried respectively by said platen and line-space wheel, a locking gear, a cam to operate the locking gear and positively hold it in locking position, and means to retract the cam and release the locking gear.

13. In a typewriting machine, the combination with a platen and a line-space wheel, of means for locking the platen and line-space wheel together, comprising a ring

gear, a pinion meshing with said gear, a locking gear, a cam to move said locking gear into interlocking engagement with the ring gear and pinion, a spring to operate the cam, and a manual device to unlock the 70 gears.

14. The combination of a platen and a line-space wheel, means for locking the platen and line-space wheel together, comprising a ring gear, a pinion, locking gears 75 on opposite sides of said pinion, rock shafts, rock arms secured to said shafts, arms carrying said locking gears and operated by said rock arms, means to operate the rock shafts in a direction to lock the gears, and 80 releasing means to operate the rock shafts in the reverse direction.

15. The combination with a platen and a platen axle, of a line-space wheel loosely mounted on said axle, a ring gear carried 85 by said wheel, a member fixed to the platen axle, a gear carried by said member in mesh with said ring gear, arms mounted for rotation about the platen axle, locking pinions carried by said arms in mesh with the ring gear, and movable into locking engagement 90 with said pinion, rock shafts mounted on said member and operatively connected to said arms, resilient means to operate said rock shafts in one direction, and a manual device for operating them in a reverse direction.

16. The combination with a platen and a line-space wheel, of a gear and pinion connected to said parts, a releasable pinion 100 to connect said gear and pinion and lock the platen and line-space wheel together, and a cam to lock said pinions together.

17. The combination with a platen and a line-space wheel, of a gear and a pinion connected to said platen and line-space wheel, independently-movable pinions to mesh with both said gear and said pinion, locking cams to hold them in mesh, and means to move them out of mesh.

18. The combination with a platen and a line-space wheel, of a gear and a pinion connecting said platen and line-space wheel, two pairs of loose pinions, springs and cams operated by said springs and urging said 115 loose pinions into mesh with the first pinion.

19. The combination of a platen, a line-space wheel, a gear, a carrier movable along said gear, a pinion on said carrier and meshing with said gear, said gear and pinion being connected to the line-space wheel and platen, four independent loose pinions on said carrier, springs, and cams operated by said springs and causing said loose pinions to mesh with said first pinion to lock the 120 carrier wherever it is placed.

20. The combination with a platen and a line-spacing wheel, of a gear, intermeshing rotary devices also meshing with said gear, an arm or member upon which one of 130

said rotary devices is pivoted, said gear and said arm or member connected to said line-space wheel and platen respectively, a spring, a lock operated by said spring and forming a positive means to hold said intermeshing devices together to connect the platen to the line-space wheel, and a finger-piece having means operable manually to separate said rotary devices while the platen is in any position of rotation to permit the platen to be rotated independently of the line-space wheel.

21. The combination with a platen and a line-space wheel, of a gear, pinions meshing with said gear, an arm upon which one of said pinions is pivoted, said arm and said gear being connected to the platen and line-space wheel respectively, a rotary device connected to each of the other pinions, a spring, locking means operated by said spring to hold said rotary devices in position to hold the pinions in engagement to connect the platen to the line-space wheel, and a finger-piece having means to actuate said rotary devices and thereby disconnect the pinions to permit the platen to be rotated independently of the line-space wheel.

22. The combination with a platen and a line-space wheel, of a train for locking the platen and line-space wheel together, a lock, means to yieldingly move the lock to locking position, and positive reacting means to hold the lock in such position.

23. In combination, a platen, a line-space wheel, a train of gears to connect the platen and line-space wheel, a lock operated by springs to lock the said train, and positive reacting means to receive the reactive force of said lock.

24. The combination of a platen and a line-space wheel, a connecting train, differential gears independently moved to interlocking engagement with said train to lock the latter with the platen and line-space wheel in any relative position of rotation, and means common to said gears for moving them together to locking and releasing position and comprising means to positively hold the gears in said locking position.
